UNITED STATES PATENT OFFICE.

JOHN HAYS HAMMOND, JR., OF GLOUCESTER, MASSACHUSETTS.

AUTOMATIC PLAYER PIANO HAVING TONE MODULATORS.

Application filed October 8, 1925. Serial No. 61,269.

This invention relates to musical instruments and particularly to automatic pianofortes.

The invention has particular reference to 5 improvements in means for controlling and modulating the music produced by automatic pianos and to imparting to the music produced by such instruments new and agreeable effects as well as to improving the 10 quality of tone produced by a particular instrument.

One of the features of the invention is the provision of an improved modulating mechanism for variably controlling the 15 intensity of the percussive action of the instrument and simultaneously modulating the sound emitted from the instrument. According to this feature of the invention a plurality of sound reflecting devices are 20 provided in the casing of the instrument whereby the sound may be directed as desired and thus the intensity of sound heard by a particular listener may be effectively modulated and controlled, and these devices 25 are operatively interconnected with the striking pneumatics of the instrument.

According to another feature of the invention the reflecting devices are arranged in separate groups corresponding in general 30 to portions of the musical scale and a separate modulating device is provided for each group so that the control of the solo or theme part may be effected independently of the control of the bass or accompaniment.

Another feature relates to improved means for coupling the several groups of reflecting devices together so that they may be controlled in synchronism.

Other objects of the invention will appear from the following description taken in connection with the accompanying drawings in which

Figure 1 is a bottom plan view of so much of an automatic player piano as is necessary to an understanding of the present invention;

Figure 2 is an enlarged cross sectional view of the variable mechanism of Figure 1;

Figure 3 is a front elevation partly in section of the piano shown in Figure 1;

Figure 4 is a section taken on the line 4-4 of Figure 3;

Figure 5 is a detailed view of a portion of the operating mechanism;

Figures 6^a and 6^b, which will be understood are to be read with the bottom edge of Figure 6^a adjoining the top edge of Figure 6^b form collectively a schematic layout 60 of an automatic playing mechanism of one well known form of automatic player piano embodying features of the invention;

Figure 7 is an enlarged view, with parts broken away, of one of the expression mechanisms or modulating devices of Figure 6^b;

Figure 8 is an enlarged view, with parts broken away, of the suction pump and pedal pneumatics of Figure 6^b;

Figures 9^a and 9^b, which will be understood are to be read with the bottom edge of Figure 9^a adjoining the top edge of Figure 9^b form collectively a schematic layout 70 of an automatic playing mechanism of another well known form of automatic player 75 piano embodying features of the invention;

Figure 10 is a view partly in section of the primary valve box, the accordion pneumatic and the expression box of Figure 9^b, the section of the expression box being 80 taken on the line 10-10 of Figure 11; and

Figure 11 is a cross section of the expression box taken on the line 11-11 of Figure 10.

Referring to the form of the invention 85 illustrated in Figures 1 to 5 there is shown so much of an automatic player instrument of the grand piano type as is necessary to an understanding of the invention.

The instrument includes a suction pump 90 11, driven by means of a belt 12 from an electric motor 13. The motor 13 is connected by a flexible cable to a source of power such as a pair of power mains 14. The pump 11 is connected by means of a pipe 95 15 to two modulating mechanisms 16 and 17, of well known construction. The outlet side of the modulating mechanism 16 is connected by a pipe 20 to the bass end of the player mechanism 20' the playing mechanisms being divided into two separate groups at approximately the middle of the keyboard. The modulating mechanism 17 is connected by a pipe 21 to the treble end of the player mechanism, 21'.

Leading from the pipe 20 is a branch pipe 22 which communicates with the interior of a pneumatic 23. Secured to the other side of the pneumatic 23 is a rod 24 which is pivoted at 25 to an arm 26 which is pivotally secured at 27 to the framework of the piano. Secured to the rod 24 is a

spring 28 the end of which is rotatably mounted on the end of an adjusting screw 30, which is held by a bracket 31 secured to the framework of the piano. The screw 30 is provided with a knurled head 32 so that it may be easily adjusted in the bracket 31.

The end of the arm 26 is provided with a slot 35, in which slides a pin 36 secured to the end of a primary valve member 37, which slides in a valve casing 38. This casing is provided with a port 40, (see Figure 2) which is in communication with a pipe 41, which in turn is connected to the pipe 15, so that it is continually under suction. A secondary valve 42 slides in the valve casing 38 and has one face adjacent to a face of the primary valve 37. The primary valve 37 is provided with an opening 43 which is always in communication with the inlet port 40. It is also provided with two longitudinal grooves 44 and 45.

The secondary valve 42 is provided with two openings 46 and 47 which continually register with two ports 50 and 51 respectively. These ports communicate with two tubes 52 and 53, which in turn communicate with two bellows 54 and 55 respectively. The bellows consist of two stationary bases 56 and 57 which are rigidly secured to the framework of the piano and a movable member 58 which is common to the two bellows and which may be moved in either one direction or the other depending upon which bellows is deflated. The outer end of the member 58 is pivoted to a link 60 which in turn is pivoted to the end of an arm 61. Pivoted to the arm 61 is a second link 62, the other end of which is pivoted to the secondary valve member 42.

The arm 61 is rigidly secured to one end of a shaft 65, which is rotatably mounted in the framework of the piano and is prevented from moving longitudinally by means of a collar 66. (See Figure 3.) Rigidly secured to the upper end of the shaft 65 is an arm 67 (see Fig. 5) to the outer end of which is pivoted a link 68, the other end of which is pivoted to a rod 70. Pivoted to the rod 70 are a plurality of arms 71 which are rigidly secured to an equal number of reflectors 72. These reflectors are pivoted at their ends to a framework 73 which is mounted inside the casing of the piano 10. Each reflector is constructed with a layer of sound insulating material for effectively suppressing sound, and an inner face of sound reflecting material 74 such as sheet aluminum or other sheet metal.

A second mechanism similar to that just described, is provided at the treble end of the piano. The controlling pneumatic of this mechanism is connected by a pipe 75 to the pipe 21. The rest of the mechanism is

similar to that already described and controls a set of reflectors 76 which are pivotally mounted in the frame 73.

Pivoted to the end of the arm 58 is a second link 77, the other end of which is connected to one arm of a bell-crank 78 which is pivoted for rotation on a pin 79, which is secured to the frame of the piano. To the end of the other arm of the bell-crank 78 is pivoted a link 81, the other end of which is connected to a rod 82. Pivoted to the rod 82 are a plurality of arms 83 which are rigidly secured to an equal number of reflectors 84. These reflectors are pivoted at their ends to a frame work 85 which is mounted inside the casing of the piano 10. These reflectors are of similar construction to the reflectors 74 and are provided with an inner face of reflecting material 86.

The reflectors 72 together with the frame 73 close the upper part of the piano forming resonating chamber 87 above the sounding board 87', which contains the strings and the reflectors 84 with the frame 85 close the lower part of the piano forming a second resonating chamber 88, below the sounding board 87'. The interior of the chambers 87 and 88 are lined with sound reflecting material 89, such as sheet aluminum.

In order to control the operation of the musical instrument a tracker bar 90 is provided which is mounted in a recess located above the keyboard of the piano. Adjacent to the tracker bar 90 are two spools 91 and 92, upon which is wound a strip 93 of perforated paper, the perforations of which are so located that they cause the proper notes to be sounded as the paper passes in front of the tracker bar 90. The spools 91 and 92 are actuated by motor mechanism of well known construction to cause the paper strip 93 to be moved across the tracker bar at any desired rate of speed. This speed is controlled by means of a speed control handle 95 located in front of the keyboard.

The tracker bar 90 is provided with two additional groups of three holes each 94 and 95 respectively. The group of holes 94 are connected by three pipes 96 to the modulating mechanism 16, and the group of holes 95 are connected by three pipes 97 to the modulating mechanism 17. These modulating mechanisms are controlled in a well known manner so that when any one or any combination of the three holes is open to the atmosphere, they will cause the modulating means to vary the suction in the pipe 20 or 21 which controls the strength with which the notes will be struck.

The remaining holes in the tracker bar 90 are connected by tubes 100 to primaries 101 which consist of pouches 102 covered by pieces of flexible leather 103. Resting upon the upper surfaces of these leathers are

valves 104 which are normally held in the position shown by the suction in the chambers 105 which are connected by ducts 103 to a longitudinal duct 107 which is in communication with the pipe 20. A bleed hole 108 is provided between the duct 106 and the pouch 102. The valves 104 are located in chambers 110 which are normally in communication with the atmosphere by means of ducts 111 and also communicate by means of ducts 112 with the interior of the striking pneumatics 113. These pneumatics are provided with arms 114 to the ends of which are pivoted striking members 115, which when the pneumatics are collapsed, strike the under side of the keys 116, causing them to be rotated about the pivot 117 thus actuating the striking actions 118 which may be of any well known and standard construction, and which are provided withhammers 120 which when the notes are struck, strike the strings 121 causing them to vibrate and produce the desired note. The strings 121 are mounted in a metallic frame 25 122 which is located just above the sounding board 87.

In the operation of the form of the invention shown in Figures 1 to 5 the paper strip 93 is caused to pass in front of the tracker bar 90 at any desired rate of speed which is controlled in the usual manner by adjustment of the handle 93'. As the paper passes over the tracker bar 90, the holes in the paper will come opposite corresponding holes in the tracker bar thus allowing air to enter the corresponding tube 100. This will cause the pouch 102 to be inflated thus raising the valve 104 which will close the port 111 and place the chamber 105 in communication with the pneumatic 113 by way of the chamber 110 and the duct 112, thus deflating the pneumatic 113. This will cause the member 115 to be moved rapidly upward, striking the under side of the key 116 which in turn will operate the action 118 causing the hammer 120 to strike the string 121 and sound the respective note. When the paper strip 93 has moved sufficiently to cover the hole in the tracker bar 90, atmospheric air will be shut off from the tube 100 and the bleed hole 108 will cause the pouch 102 to be deflated, thus allowing the valve 104 to be seated which will shut off the supply of suction to the pneumatic 113 and allow it again to be connected to the atmosphere through duct 111 thus causing the pneumatic 113 to be inflated, and therefore causing the member 115 to drop back to the position shown in Figure 4. In a similar manner whenever a hole in the paper 93 passes in front of a hole in the tracker bar, the corresponding note will be struck.

When holes in the paper come opposite the group of holes 94 in the tracker bar 90, they will allow air to pass through the tubes

96 to the modifying means 16 which causes the suction in the pipe 20 to be varied according to the hole or combination of holes of the group 94, which are uncovered, as will subsequently appear. The modulated 70 suction in the pipe 20 is communicated to the duct 107 and causes whichever pneumatics 113 which may be operated, to strike the keys a blow, the force of which is determined by the suction in the pipe 20. In this 75 manner any desired strength of note may be produced.

The suction in pipe 20 is communicated by means of pipe 22 to the pneumatic 23 causing this to be collapsed, an amount proportional to the differential between the suction in the pipe 20 and the tension of the spring 28. The rod 24 moves the primary valve 37 to a corresponding position by means of the arm 26. If, for example, the rod 24 is 80 moved downward, as shown in Figure 1, due to an increase of suction in pipe 20, the primary valve 37 will also move downward as seen in Figure 2, thus communicating the suction from the port 40 through the 90 hole 43 to the passage 46 thence through port 50 and tube 52 to the pneumatic 54 which is then collapsed, causing the link 60 to be moved downwardly, which in turn rotates the arm 61 in a clockwise direction. This 95 causes the link 62 to pull the secondary valve 42 downwardly until the section between the openings 46 and 47 has covered the hole 43, thus shutting off the suction from the pneumatic 54. This will stop the motion of the 100 arm 61 which will then remain in that position until the primary valve 37 has been again moved under the action of the pneumatic 23. It is evident, therefore, that the arm 61 will take up a position corresponding 105 to the amount of suction in the pneumatic 23 and, therefore, corresponding to the suction in the pipe 20 which as previously stated, controls the strength with which the notes will be struck. The tension of the 110 spring 28 may be adjustably varied, and thus the action of the arm 61 may be varied as desired.

The arm 61 being rigidly secured to the shaft 65, causes this to be rotated, which in 115 turn causes the rotation of the arm 67, (see Fig. 5), in a counter-clockwise direction. This arm being connected by link 68 to the rod 70 causes this to be moved to the left as seen in Figure 5, thus rotating the reflectors 72 in a counter-clockwise direction which will increase the opening between these shutters. The angular displacement of the reflectors from the closed position will, therefore, be proportional to the suction in the pneumatic 23, which in turn is proportional to the strength with which the notes will be struck.

This will control the volume of sound heard by a listener according to the inten- 130

sity of the percussive action, and therefore will produce an additional modulation of the sound emitted by the piano.

A similar action takes place at the treble end of the piano, causing the swell shutters 76 to open an amount proportional to the suction in the pipe 21. In this way the sound emitted from either section of the piano by the reflectors will be proportional to the strength with which the strings in this section are being struck by the pneumatics 113.

The reflectors 84 are controlled by the arm 58 so that as this arm moves downwardly, as just described, the bell-crank 78 will be rotated in a clockwise direction about the pivot 79. This will cause the link 81 and the rod 82 to be moved to the left, thus opening the reflectors 84 in a similar manner to that just described in connection with the reflectors 72.

In the modified form of the invention shown in Figures 6 to 8, the system is shown as applied to one commercial form of automatic piano player. This system consists of a tracker bar 150 over which the standard player piano paper is moved by any well known means, two expression mechanisms 151 and 152 for regulating the suction to the bass and treble player pneumatics 153 and 154 respectively, two crescendo pneumatics 155 and 156 which modify the action of the expression mechanisms as will appear hereinafter, a loud pedal pneumatic 158, a suction pump 160 for producing the suction necessary to operate the player, a control mechanism 161 for causing the piano to be played either soft, medium or brilliant, a reroll mechanism 162 which when operated shuts off the supply of suction to the player pneumatics 153 and 154, two shutter control systems 163 and 164 which operate two sets of reflectors 165 and 166 which are located above the bass and treble divisions of the strings respectively.

The tracker bar 150 is provided with a plurality of holes which are divided into three groups 170, 171 and 172. The group 170 consists of seven holes which control the expression mechanisms for the bass end and the loud pedal. The group 171 consists of eight holes which control the expression mechanism at the treble end, the soft pedal mechanism and the reroll mechanism. The group 172 consists of eighty-three holes which control the playing of the notes of the piano. The group 170 comprises seven holes 173 to 179 which communicate with tubes 183 to 189 respectively.

The three tubes 184, 186 and 188 are connected to three chambers 191, 192 and 193 in the expression mechanism 151 (see Figure 7). Each of these chambers is covered by a flexible leather pouch 194 upon which rests

a valve 195 which consists of upper and lower members interconnected by a rod. These valves are located in chambers such as 196 and are connected by passages 197 to a duct 198. The chambers 196 are connected by circular passages 200, through which the stems of the valves 195 pass to the atmosphere. These passages are normally closed to the atmosphere by the upper members of the valves 195. The passages 200 are connected by ducts 201 to secondary ducts 202 which communicate with three pneumatics 203, 204 and 205. The lower ends of the ducts 202 communicate with chambers such as 207 which are provided with valves 208, mounted upon pouches 209. Below the pouches 209 are chambers 210 which communicate with a duct 211. Between the chambers 191 and 207 are ducts 212. From these ducts to the chambers 196 are small bleed holes 213.

The duct 198 communicates with a chamber 215 in which is mounted a valve 216, consisting of an upper and lower member connected by a stem. Communicating with the chamber 215 is a cylindrical chamber 217 through which the stem of the valves 216 passes. The duct 211 is in communication with the chamber 217. The valve 216 is mounted on a pouch 218 which covers a chamber 220 which is in communication with the tube 189. The tube 189 is connected to the duct 198 by means of a small bleed hole 221.

The duct 198 communicates with a chamber 222 which is provided with a pouch 223 covering a second chamber 224, which is in communication with a tube 225. The chamber 222 is connected by a duct 226 to a large chamber 227 which is provided with two openings 228 and 230. The opening 228 is covered by a valve 231 which operates in a chamber 232 which communicates with a large supply tube 233. The valve 231 is carried by a rod 234, the upper end of which is secured to a yoke 235 which is pivoted at 236 and is secured to the tops of the pneumatics 203, 204 and 205. The lower end of the rod 234 is adjustably secured to one side of a pneumatic 240 the interior of which communicates with a tube 241.

The opening 230 is covered by a valve 242 secured to a rod 243 the lower end of which is adjustably secured to one side of a pneumatic 244. Surrounding the rod 243 between the arm of the pneumatic 244 and the expression mechanism 151 is a spring 243'. The interior of the pneumatic 244 communicates by means of a duct 245 with a chamber 246 which is provided with an atmospheric port 247. In the chamber 246 is mounted a valve 250 having a stem 251 which passes through an opening leading from a chamber 246 to a chamber 252. The lower end of the stem 251 rests upon a pouch 253.

which covers a chamber 254 which is in communication with a tube 255. The chamber 252 communicates by means of a duct 256 with a chamber 257 which is in communication with a pipe 258. A small bleed hole 259 is provided which connects the chamber 254 with the duct 256.

The crescendo pneumatic (see Fig. 7) consists of a bellows 260, mounted on a base 261. The bellows 260 carries an arm 262 to which is attached one end of a spring 263 the other end of which is secured to a second arm 264 mounted on the base 261. Pivotaly mounted on the base 261 is an arm 265 which oscillates about the edge 266 as a fulcrum. The arm 262 is provided with a lug 265' normally in contact with the arm 265. A spring 266' is secured to the base 261 for retracting the arm 265. Normally the arm 265 covers two ports 267 and 268 which communicate respectively with two ducts 270 and 271. The duct 270 communicates at one end with the tracker bar tube 187 and at the other end with a chamber 272. The duct 271 communicates at one end with the tracker bar tube 183 and at the other end with a chamber 273. The chambers 272 and 273 are connected by a small bleed hole 274 which communicates with a chamber 275. This chamber is separated from the chambers 272 and 273 by two pouches 276 and 277. Resting upon these pouches are two valves 280 and 281 which are located in chambers 282 and 283 respectively. Surrounding the stem of the valve 281 is a spring 281' which tends to maintain the valve 281 in the position shown in the drawing. The chambers 282 and 283 communicate with the chamber 275 by means of circular ports and communicate with the atmosphere by means of ports 284 and 285 respectively. The chamber 282 is in communication, by way of a duct 286, with a chamber 287. Covering this chamber is a pouch 288 to which is secured a valve 289 which operates in a chamber 291. This chamber communicates with the chamber 283 by means of a duct 292. A small duct 293 leads from the duct 292 to the interior of the bellows 260. Leading from the top of the bellows 260 is a pipe 294 which communicates with the interior of the bellows 260. The pipe 241 from the pneumatic 240 also communicates with the interior of the bellow 260.

The loud pedal mechanism 157 consists of a pneumatic 300, to the upper side of which is connected a rod 301, which when the pneumatic is deflated, causes the loud pedal to be operated. The interior of the pneumatic 300 communicates by means of a duct 302 with a chamber 303 in which is mounted a valve 304. The chamber 303 is provided with an atmospheric vent 305 and with a port 306, which communicates with a chamber 307, the

lower part of which is covered by a pouch 308, upon which rests the stem of the valve 304. The chamber 307 communicates with the suction supply pipe 310.

Under the pouch 308 is located a chamber 311 which is in communication with the tube 185. A small bleed hole 312 is provided which connects the chamber 311 with the pipe 310.

The expression mechanism 152, the crescendo pneumatic 156 and the soft pedal pneumatic 158 are similar in construction to the expression mechanism 151, the crescendo 155 and the loud pedal pneumatic 157 respectively and it is thought that the description given for one will suffice for all. The primary mechanism 153 and 154 are similar to those disclosed in Figure 4, and described in connection therewith.

The pump unit 160 is driven by an electrical motor 315 operated by a convenient source of electrical power and belted to a pulley 316 mounted on a suction pump 317. The pump 317 which consists of four pneumatics 318 operated successively from the shaft of the pulley 316. When any of the pneumatics 318 are opened air is drawn from a chamber 320 through check valves 321 into the interior of the pneumatics 318 and when these are collapsed, air is forced through check valves 322 into the interior of the pump 317 from which it escapes through holes in the casing 323. On the lower side of the pump 317 is mounted a reservoir 324 which communicates with the passage 320 by means of a port 325. Inside the reservoir 324 is mounted a spring 326 which tends to hold the reservoir open. On one side of the pump is mounted a pneumatic 330 the interior of which communicates with a tube 331. The top of this pneumatic carries an arm 332 the end of which is connected by a spring 333 to the frame of the pump 317. A valve 334 is provided in the passage 320 which normally covers a port 335. The valve 334 is operatively connected to the arm 332 by means of a spring 336.

The duct 320 is provided with two openings 340 and 341 in communication with a chamber 342 which is provided with an opening 343, communicating at the left with the pipe 233 from the expression mechanism 151 and at the right corresponding with the pipe 233' from the expression mechanism 152. A pouch 346 is located under the opening 343 and covers a chamber 347 which is connected to a tube 348. A small bleed hole 349 connects the chamber 347 with the chamber 342.

The tube 331 communicates with a chamber 350 located in a valve block 351 which forms part of the control mechanism 161. The chamber 350 is provided with an atmospheric port 352 and an internal port 353 which communicates with a second cham- 130

ber 354. This second chamber communicates with two check valves 355 and 356 which in turn communicate with tubes 357 and 358. The tube 357 is connected to the pipe 258 of the expression mechanism 151, and the tube 358 is connected to a corresponding pipe of the second expression mechanism 152. In the chamber 350 is located a valve 360 the stem of which rests upon a pouch 361 which covers a chamber 362 which is in communication with a tube 363. A bleed hole connects the chamber 362 with the chamber 354. The tube 363 leads to a three-position control valve 364, which is shown in its central or medium position. The valve 364 is provided with an atmospheric port 365 which at suitable times communicates with the tube 363. By rotating this valve in a clockwise direction the port 365 will communicate with the tube 255. The tube 255 is connected to a corresponding tube 255' of the modifying means 152.

The tube 348 communicates with a passage 370 in the reroll valve mechanism 162. The passage 370 communicates with the chambers 371 and 372, and is provided with a valve 373 which rests upon a pouch 374 covering a chamber 375. The chamber 371 is provided with an atmospheric port 376, and the chamber 372 is connected by a pipe 377 to the pipe 233' of the second expression mechanism 152. A small bleed hole 378 connects the chamber 375 with the chamber 372. The chamber 375 communicates with a tube 380, the other end of which communicates with a hole 381 provided in a plate 382. Slidably mounted upon the plate 382 is a disk 383 which is carried by an arm 384 which controls the rewind mechanism.

The reflector control system 163 consists of a pneumatic 390 which is connected by a pipe 391 to the pipe 258. This pneumatic is similar to that shown in Figure 1, at 23 and the rest of the control mechanism, including the reflectors, is the same as that described in connection with Figures 1 to 5.

The tube 225 is connected to the bottom of a valve casing 393 in which slides a plunger 394 provided with a longitudinal hole 395. A spring 396 is provided under the plunger 394 to hold it in its uppermost position. An atmospheric port 397 passes through the wall of the valve casing 393, and is normally covered by the plunger 394, the upper end of which is tapered, so that when it is depressed it will gradually uncover the port 397. A similar control valve 398 is provided which is connected to the pipe 225' of the expression mechanism 152.

In the operation of the embodiment of the invention shown in Figures 6, 7 and 8, the note holes 172 in the tracker bar 150 are uncovered by the perforations in the music roll, thus allowing air to enter these pipes,

which in turn operate the striking pneumatics as described in connection with the structure of Figure 4.

When a hole in the paper comes opposite the hole 175 in the tracker bar 150, air is admitted to the tube 185 and into the chamber 311, raising the pouch 308 and thus lifting the valve 304 which closes the atmospheric port 305 and connects the pneumatic 300 to the suction supply in chamber 307, thus collapsing the pneumatic 300 and pulling down on the rod 301 which causes the loud pedal mechanism to be operated. In a similar manner when a hole in the paper uncovers the corresponding hole of the group 171 air is admitted to the soft pedal primary 158, thus causing its pneumatic to be collapsed and operating the soft pedal action.

The suction produced by the pump 160 is maintained constant by means of the valve 334 which normally covers the port 335, if the suction in the pump should increase beyond a predetermined amount which is dependent on the tension of the spring 336, the valve 334 will automatically be pulled open by the pressure of the atmospheric air, thus allowing air to enter the chamber 320 and reducing the suction in this to the predetermined value.

If it is desired to increase the suction in the pipes 233 and 233' the control lever 364 is rotated in a counter-clockwise direction to the position marked brilliant. In this position the port 365 registers with the opening of the tube 363, thus allowing air to enter the chamber 362 and inflating the pouch 361, thus raising the valve 360 which closes the port 352 and connects the tube 331 with the suction chamber 354, thus causing the air to be withdrawn from the tube 331 and collapsing the pneumatic 330 which rotates the arm 332 in a clockwise direction thus increasing the tension on the spring 336. This will not occur, however, until the suction in the chamber 354 is sufficiently great to overcome the pull of the spring 333. The suction in the chamber 354 is dependent on the suction in the tubes 357 and 358 and will be the same as the greater of these. The amount of suction in the pipes 357 and 358 is determined by the modulating means 151 and 152 and will be explained more fully hereafter. The check valves 355 and 356 are provided so as to prevent the suction from passing from one tube to the other.

When the reroll lever 384 is moved to the right, in order to actuate the reroll mechanism, the hole 381 is uncovered allowing air to enter tube 380 thus inflating pouch 374 which lifts the valve 373 shutting off the tube 348 from the suction and allowing air to enter through port 376, passing through tube 348 to the chamber 347 inflat-

ing the pouch 346 which covers the hole 343 thus shutting off the supply of suction to the striking pneumatics.

In the operation of the expression mechanism 151, the suction from the pump passes through the pipe 233 to the chamber 232 thence through the opening 228 into the chamber 227 from which it passes through the opening 230 into the chamber 257; from which it goes through the pipe 258 to the bass pneumatics 153. The position of the valve 231 is determined by the suction in the pneumatic 240 pushing upwardly on the rod 234 and the combined suction in the pneumatics 203, 204 and 205, any one or any combination of which may be on, as will be presently described, pushing downwardly on the rod 234. If the suction in the chamber 227 is less than that required to hold the valve 231 on its seat, this valve will be lifted by the suction in the chamber 232 thus increasing the suction in the chamber 227. This increased suction will pass through the duct 226, chamber 222, duct 198, pipes 197, chambers 196, ducts 201, secondary ducts 202, into the pneumatics 203, 204 or 205 depending upon which valves 195 are open. This will increase the suction in these pneumatics, thus forcing the rod 234 down with greater strength, thus tending to close the valve 231. This operation, therefore, maintains the suction in the chamber 227 at a predetermined amount depending upon which of the pneumatics 203, 204 or 205 are operating and depending upon the suction in the pneumatic 240, it will be noticed that the pneumatics 203, 204 and 205 are at different distances from the fulcrum 236 of the arm 235. Seven different combinations of pressure may, therefore, be obtained upon the rod 234 depending upon which one or combination of pneumatics 203, 204 and 205 are deflated, thus if 203 alone is deflated the first intensity will be produced. 204 will produce the second, 203 and 204 will produce the third, 205 alone will produce the fourth, 205 and 203 the fifth, 205 and 204 the sixth, 205, 203 and 204 the seventh.

The pneumatics 203, 204 and 205 are controlled by the valves 195 which are operated by the pouches 194. Thus, if for example, when the hole in the paper comes opposite the hole 174 in the tracker bar 150, air is admitted to the tube 184 and enters the corresponding pouch 191 inflating same and causing the valve 195 to move upwardly, shutting off the suction from the pneumatic 203 and allowing air to enter through the passage 200, duct 201, secondary duct 202 to the pneumatic 203 thus inflating it. At the same time air passes into the chamber 207 and through the duct 212 into the chamber 191, under the pouch 194 so that when the hole in the paper passes from in front of the hole 174 in the tracker bar this pouch will remain inflated

with air, thus holding the valve 195 open and the pneumatic 203 inflated.

In a similar manner either the pneumatic 204 or 205 may be inflated by holes in the paper coming opposite holes 176 and 178 respectively in the tracker bar 150. When it is desired to deflate the pneumatics 203, 204 and 205, a hole in the paper comes opposite the hole 179 in the tracker bar 150 and allows air to pass through tube 189 to chamber 220, thus inflating the pouch 218 and lifting the valve 216 which allows air to enter the duct 211 and thence into the three chambers 210. This inflates the three pouches 209 and lifts the three valves 208, closing the opening to the secondary duct 202. The bleeds 213 then suck the air from the chambers 191, thus causing the pouches 194 to be deflated and the valves 195 lowered to the positions shown in Figure 7. This shuts off the atmosphere from the pneumatics 203, 204 and 205 and connects them to the suction chambers 196 thus deflating the three pneumatics. If it is desired to put any of them on again, suitable holes are placed on the paper so as to come opposite the proper holes in the tracker bar as previously described.

The suction in the pneumatic 240 can be changed at either a fast or slow rate or may be maintained at any desired point within certain limits. The suction in this pneumatic is the same as that in the bellows 260 as they are connected together by the tube 241. If it is desired to increase the suction at a slow rate, a hole in the paper comes opposite the hole 173 in the tracker bar 150 and air is admitted to tube 183 and thence through duct 271 to chamber 273 inflating the pouch 277, thus moving the valve 281 upwardly against the action of the spring. This shuts off chamber 283 from the atmospheric port 285 and connects it to the suction chamber 275. Air is then sucked through the small duct 293 from the bellows 260 deflating it at a slow rate against the action of the spring 263.

If it is desired to change the suction in the pneumatic 240 at a rapid rate, holes in the paper appear opposite holes 177 and 173 in the tracker bar 150, the former allowing air to enter the tube 187, thence through duct 270 into chamber 272 inflating the pouch 276 and lifting the valve 280, and the latter lifting the valve 281 as just described. This closes the atmospheric port 284 and connects the duct 286 to the suction chamber 275, thus sucking the air from the chamber 287 and pulling the valve 289 away from the opening to the tube 294 which is then connected to the suction chamber 275, by the duct 292 and under the valve 281. This causes air to be rapidly withdrawn from the bellows 260, deflating it at a rapid rate, which at the same time deflates the bellows 130

240 at an equal rate. By locating holes in the paper in sufficient numbers and at proper intervals, the pneumatic 240 may be deflated either rapidly or slowly or may be maintained at an intermediate suction by suitably placing the holes in the paper which cooperate with the holes 173 and 177. In order to give a rapid collapse of the bellows 260 both ports 173 and 177 can be opened simultaneously.

When both holes 173 and 177 are closed, the bellows 260 will be connected to the atmosphere, through duct 293 and atmospheric port 285. The bellows will then open under the action of the spring 263 until the lug 265 engages the arm 265, rotating it in a counter-clockwise direction about the point 266. This will expose the port 268 which lifts the valve 281 as previously described, thus connecting the bellows 260 to the suction chamber 275 through the small duct 293. If the bellows 260 should be opening very rapidly, it will rotate the lever 265 enough so that it also uncovers the port 267, thus allowing air to enter the chamber 272, lifting the valve 280, thus dropping the valve 289, and connecting the bellows 260 to the suction through the pipe 294 as previously described. Thus, when both holes 173 and 177 are covered the suction in the bellows 260 will be maintained at a high value which is determined by the tension of the spring 263.

By proper positioning of the holes in the paper, in sufficient number and at proper intervals, it is evident that any one or combination of the pneumatics 203, 204 and 205 may be deflated intermittently at desired rates and the pneumatic 240 may be thereby positioned to control the suction pressures. Thus, the striking pneumatics can be operated with any desired force. If it should be desired to cut down the pressure in the pneumatics 153 to a predetermined ratio of the pressure in the chamber 227, the control valve 364 is moved in a clockwise direction to the position "Soft", thus bringing the port 365 in line with the opening of the tube 255 admitting air to this tube which inflates the pouch 253 lifting the valve 250, which closes the atmospheric port 247 and connects the duct 245 to the chamber 252, which is under the same regulated suction as the chamber 257. This causes the pneumatic 244 to be collapsed by the same amount of suction as is in the chamber 257. This will close the valve 242 which will remain closed until the suction in the chamber 257 has decreased sufficiently to cause this valve to be opened, thereby increasing the suction in the chamber 257 and as the pneumatic 244 is under the same suction this will start to collapse, thus closing the valve 242 again. In this way the suction in the cham-

ber 257 is always maintained in a certain ratio to that in the chamber 227, which causes the notes to be struck softly but with the same relative intensity as they were when the control valve was at "Medium." 70

The regulated air in the pipe 258 passes through pipe 391 to the pneumatic 390 which is collapsed an amount proportional to the suction in the pipe 258 and operates to control the swell shutters 165 in a manner similar to that described in connection with Figures 1 to 5. 75

If it is desired to control the expression of the piano by hand, the plunger 394 is depressed with the finger thus uncovering the atmospheric port 397 an amount depending upon how far the plunger has been depressed. This allows a certain quantity of air to pass through the duct 395 and tube 225 to the chamber 224, inflating the pouch 223 and cutting off the supply of suction to the duct 198. 80

The expression mechanism 152 and the crescendo pneumatic 156 are controlled in a manner similar to that just described by means of the group of holes 171. 85

In the modified form of the invention shown in Figures 9^a and 9^b, 10 and 11, the system is shown as applied to another commercial form of automatic piano. This mechanism consists of a tracker bar 401, two cut-out blocks 402 and 403, a primary valve box 404, two accordion pneumatics 405 and 406, an expression box 407, a theme primary valve box 408, a bass and treble 100 stack of pneumatics 410 and 411, a bass and treble modulator control mechanism 412 and 413, a set of bass and treble reflectors 414 and 415, a regulator pneumatic 417 and a suction pump 418. 105

The tracker bar 401 is provided with a group of holes 421 which communicates with an equal number of tubes 422. Two groups of holes are provided adjacent to the group 421 which are connected respectively to two 110 groups of tubes 423 and 424. The tubes included in the groups 422, 423 and 424 control the striking of the notes in a well known manner. Located directly above these two groups of holes are two secondary groups 115 of holes, the left hand group of which communicate with four tubes 425, 426, 427 and 428 and the right hand group which communicates with four tubes 430, 431, 432 and 433. The group of tubes 423 and the four tubes 425-428 pass through the cut-out block 402 which when it is in the position shown, shuts off the group of tubes 423 but leaves the tubes 425-428 open. When this cut-out block is moved manually to the other position the tubes 425-428 will be shut off and the group of tubes 423 will be open. In a similar manner the groups of tubes 424 and the tubes 430-433 are controlled by the cut-out block 403. 120

The tracker bar 401 is also provided with six holes (three on each side) 435—440 which communicate respectively with tubes 441—446. The tubes 441 and 445 control the reroll and the motor in a well known manner which need not be more fully described.

The tube 443 is connected by a branch tube 447 to a valve 448 controlled by a handle 449 which is pivoted for rotation upon a block 450 and is provided with a felt pad 451 which covers the opening to the tube 447. The valve 448 is held in the position shown by means of a spring 452. The tube 444 is connected by a branch tube 455 to a valve 456 controlled by a handle 457 which is pivoted for rotation upon a block 458 and is provided with a felt pad 460 which covers the opening to the tube 459. The valve 456 is held in the position shown by means of a spring 461.

The tubes 425—428 and 430—433 lead to the primary valve box 404 (see Fig. 10) where each one communicates with a chamber 463, each of which is covered by a pouch 464 upon which rests a valve 465 which is positioned in a second chamber 466. All of the chambers 466 are in communication with each other by means of ports 467, and are connected to a supply pipe 468. Between each chamber 466 and its corresponding tube is a bleed hole 470. The upper part of each valve 465 is located in a chamber 471 which communicates with the atmosphere through port 472. The chambers 471 communicate with flexible tubes 475 to 478 and 480, to 483. These are so arranged that the tubes 425—428 control the supply of suction to the tubes 475—478 respectively and the tubes 430—433 control the supply of suction to the tubes 480—483 respectively.

The tubes 475—478 communicate with four bellows 485—488 of the accordion pneumatics 405 and the tubes 480 to 483 communicate with four corresponding bellows of the accordion pneumatic 406.

The accordion pneumatics 405 are mounted upon the base 490 and are connected by means of a link 491 to an arm 492 which is loosely mounted upon a shaft 493. Upon this shaft is also loosely mounted an arm 494 which is connected by means of a rod 495 to an arm 496 which is rigidly secured to a shaft 497 which is mounted for rotation in a bearing 498 secured to the block 490. Rigidly secured to the other end of the shaft 497 is an arm 500 to the other end of which is pivoted a rod 501 the other end of which is connected to a bell crank 502, which is mounted for rotation upon the block 490. The other end of the bell crank 502 is provided with a handle 503. The bell crank 502 is held in the position shown by means of a spring 504. The shaft 493 is supported in bearings 505 which are mounted upon the

expression box 407 and has fastened to it an arm 506 which carries at its end a pin 506' which rests upon the arms 492 and 494. Secured to the other end of the shaft 493 is an arm 507, to the end of which is pivoted a link 508, the other end of which is pivoted to an arm 509, which is rigidly secured to a shaft 510 mounted for rotation in the side of the expression box 407. To the other end of the shaft 510 is rigidly secured an arm 511 which is pivoted to one end of a floating valve 512, the other end of which is connected by a link 513, to the movable wall of a bellows 514.

A similar mechanism is used in conjunction with the accordion pneumatics 406 and is manually controlled by a handle 515 mounted on the block 458. This mechanism also controls one end of a floating valve 516 (see Figure 11) which is similar to the floating valve 512. The other end of the valve 516 is connected by a link 517 to the top of a pneumatic 518. Secured to the movable walls of the pneumatics 514 and 518 are two arms 520 and 521 to which are secured the ends of two springs 522 the other ends of which are secured to a T shaped member 523 mounted upon the expression box 407. The interior of the pneumatic 514 is connected by means of a duct 525 with a chamber 526 which is provided with two check valves 527 and 528 which cover ports 530 and 531 leading to chamber 532 and 533 which communicate with two pipes 534 and 535 which form the supply pipes to the two pneumatic stacks 410 and 411. The chambers 532 and 533 are provided with ports 536 and 537 which are controlled by valves 540 and 541. The interiors of these valves are in communication with two tubes 542 and 543. The valves 540 and 541 consist of two soft leather pouches 544 and 545 which are covered by two diaphragms 546 and 547. The valves 540 and 541 are located in chambers 550 and 551 which are connected together by means of a passage 552. The chamber 551 communicates with the interior of the bellows 518 by means of a duct 553.

The floating valves 512 and 516 cover two ports 554 and 555 which communicate with a chamber 556 which is provided with a port 557. Co-operating with the port 557 is a valve 558 which is rigidly secured to a shaft 559 which is mounted for rotation in the sides of the expression box 407. Rigidly secured to each end of the shaft 559 are two sets of arms 561 and 562, the former set of which is kept pressed upon the arms 509 by means of two springs 563 which are connected from the other arms 562 to two lugs 564 secured to the sides of the expression box 407. The valve 558 is located in a chamber 565 which is provided with a port 566 in the side of the expression box 407.

The tubes 543 and 542 communicate with

two chambers 570 and 571. The chambers 570 and 571 are provided with ports 572 and 573 which connect them with the atmosphere. They are also provided with two ports 574 and 575 in which slide two valves 576 and 577, the lower parts of which are in a chamber 578 and rest upon two pouches 580 and 581 which cover two chambers 582 and 583 which are connected to the two tubes 444 and 443. The chamber 578 is connected to a supply pipe 584 which communicates with the two chambers 582 and 583 by means of two bleed holes 585 and 586.

The chamber 556 in the expression box 407 is in communication with a pipe 590, the other end of which communicates with a chamber 591 in the modulator pneumatic 417. This chamber is provided with a port 592 which communicates with a bellows 593 in which is mounted a knife valve 594 which is pivoted at 595 and is provided with a felt pad 596 which when the bellows is collapsed closes the port 592. Secured to the top of the bellows 593 is an arm 597 to the end of which is connected a spring 598, the other end of which is connected to an arm 599 which is secured to the side of the modulator pneumatic 417. The knife valve 594 which is connected by a link 601 to the movable wall of the bellows 593 controls a port 602 which communicates with a chamber 603. This chamber is provided with a second port 604 which communicates with a longitudinal chamber 605 in which is mounted a small pneumatic 606 which when inflated closes a port 607 which connects the chamber 605 to the chamber 591. The interior of the pneumatic 606 is connected to the interior of the chamber 605 by means of a bleed hole 608 and is also connected to a tube 610 which runs to a port 611 in a block 612 located adjacent to the key board of the piano. Mounted upon this block is an arm 613 which, when it is in the "Concert" position shown, covers the port 611. When this lever is in the "Soft" position, it uncovers the port 611, thus allowing air to enter the tube 610. The chamber 603 is connected by a pipe 615 to the suction pump 418 which is provided with a large pulley 616 which is driven from a suitable electric motor 617 by means of a belt 618.

To the pipe 615 is connected a branch pipe 620 which is connected to the pipe 584 and which is also connected to a port 621 located in a bellows 622 which forms part of the pedal regulator pneumatic 416. Secured to the movable wall of this bellows is a knife valve 623 which controls the opening of the port 621. Fastened to the outside of the top of the bellows 622 is a spring 624, the other end of which is secured to a block 625. The interior of the bellows 622 communicates by means of a duct 626, with a chamber 627 which is provided with two pouches 628 and 629 which cover two chambers 631 and 632. The chamber 627 communicates with the tube 468. These chambers are connected to the duct 626 by means of two bleed holes 633 and 634. The chambers 631 and 632 communicate with the tubes 442 and 446 respectively. Resting on the pouches 628 and 629 are two valves 635 and 636 the stems of which pass through ports 637 and 638 which connect the chamber 627 with two chambers 640 and 641. These chambers are provided with atmospheric ports 642 and 643 and are also connected to tubes 644 and 645 which in turn are connected to two pneumatics 646 and 647. The pneumatic 646 controls the loud pedal action of the piano by means of a rod 648 and the pneumatic 647 controls the soft-pedal action of the piano by means of a rod 649.

To the pipe 534 is connected a branch pipe 650, the other end of which is connected to a pneumatic 651 on the top of which is mounted a rod 652, the other end of which is pivoted to an arm 653 which is mounted for rotation about the point 654. To the end of the rod 652 is connected a spring 655, the other end of which is rotatably mounted upon the end of an adjusting screw 656 which is threaded into a bracket 657. The outer end of the arm 653 is provided with a slot 660 in which slides a pin 661 carried on the end of a primary slide valve 662 which slides in the valve casing 663. This valve is identical in construction with that shown in Figure 2 and is provided with a secondary valve 664, a supply pipe 665 which is connected to the pipe 620 and two tubes 666 and 667 which are connected to two bellows 668 and 669 between which is mounted an oscillating member 671 to the end of which is connected a link 672 the other end of which is pivoted to an arm 673, to which is connected a link 674 the other end of which is connected to a secondary slide valve 664.

The arm 673 is rigidly secured to a shaft 675 which passes through the framework of the piano and has secured to its upper end an arm 676. The end of the arm 676 is connected to a link 677, the other end of which is connected to a rod 678. To this rod is pivoted a plurality of arms 679, mounted upon the tone reflectors 414. The pneumatic 651, valve 663, bellows 668 and 669, and arm 673, are viewed from beneath the piano looking upward, while the arm 676 and its associated parts are viewed from above, looking down from the top of the piano.

Mounted at the other end of the piano is a similar mechanism consisting of a pneumatic 680 which is connected by a pipe 682 to the pipe 535, a valve 683 which is supplied by a pipe 684 connected to the pipe 615 and which is connected by two tubes 685 and 686 to the chamber 627.

685 and 686 to a double bellows 687 which controls the motion of an arm 688 secured to a shaft 689 to the other end of which is fastened an arm 691 which controls the tone reflectors 415.

In the operation of the form of the invention shown in Figures 9^a, 9^b, 10 and 11, the paper strip is caused to pass over the tracker bar 401 in a well known manner and is provided with holes which when they come opposite holes in the tracker bar allow air to enter the corresponding tubes. When a perforation in the paper comes opposite any of the holes in the group 421, air is admitted to the corresponding tubes of the group 422 and causes the corresponding note of the piano to be struck. If the cut-out blocks 402 and 403 are in the opposite position from that shown in Figure 9^a, the groups of pipes 423 and 424 will be connected to the corresponding holes in the tracker bar 401 and any perforations in the paper strip which come opposite the holes in the tracker bar will cause the corresponding notes to be struck. If, however, the cut-out blocks 402 and 403 are in the position shown in Figure 9^a, the groups of tubes 423 and 424 will be disconnected from the tracker bar and therefore the notes controlled by them cannot be sounded.

When perforations in the paper strip come opposite any of the holes 425—428 and 430—433, air will enter the corresponding tubes and actuate the corresponding primary valve 404, thus suppose air enters the tube 425. It will pass into the chamber 463 (see Fig. 10) thus elevating the pouch 464 and raising the valve 465. This closes the atmospheric port 472 and connects the chamber 466 to the chamber 471 thus connecting the bellows 485 to the suction which is constantly in the chamber 466 as this is connected to the suction supply tube 468 by the port 467. This causes the bellows 485 to be deflated. If air enters the tube 426, the bellows 486 will be collapsed in a similar manner. As the bellows 485, 486, 487 and 488 are so constructed that when they collapse they will move through distances proportional to the numbers 1, 2, 4 and 8, any desired motion of the arm 492 may be produced by collapsing any one of these bellows or any combination of them. Thus, for example, if the bellows 485 is collapsed, a motion proportional to 1 will be produced. If 485 and 486 are both collapsed a motion proportional to 3 is produced, and if 485, 486 and 488 are collapsed, a motion proportional to 11 is produced. In this way by providing the proper perforations in the paper strip any desired motion of the arm 492 may be produced. This motion is transmitted by means of a pin 506' to the arm 506 which by means of the shaft 493 rotates the arm 507 in a counter-clockwise direction,

thus moving the link 508 to the right which rotates the arm 509 in a clockwise direction which in turn rotates the arm 511 in the same direction thus moving the left hand end of the floating valve 512 downwardly. The location of the end of the floating valve will therefore be determined by the amount that the accordion pneumatic 405 has been collapsed which in turn depends upon the arrangement of the perforations in the paper strip passing over the tracker bar. The position of this end of the floating valve 512 will determine the amount of suction in the pneumatic 514 for as this is collapsed due to the air being sucked out through the port 554 into the chamber 556 which is constantly under suction, it will cause the bellows to be collapsed which will cause the valve 512 to close off the port 554, thus shutting off the suction to this bellows. As soon as this happens the spring 522 will tend to open the bellows which will thus cause the port 554 to be opened. This action will continue thus keeping the suction in the bellows 514 at a constant amount depending upon the position of the left hand end of the valve 512 and the strength of the spring 522. As the position of the left hand end of the valve 512 is changed, the position of the movable wall of the bellows 514 when the valve 512 shuts off the port 554, will also be changed, and therefore the tension of the spring 522 when the port 554 is shut off, will be changed a corresponding amount. In this way any desired suction may be produced in the bellows 514. This can also be controlled by means of the handle 503 which as it is moved to the right will cause, by means of the rod 501, a counter-clockwise rotation of the shaft 497, thus lifting the rod 495 which will cause a counter-clockwise rotation of the arm 494 which by means of the pin 506' will cause a corresponding rotation of the shaft 493, thereby changing the amount of suction in the bellows 514 in a manner similar to that just described.

In a similar manner the accordion pneumatics 406 are controlled by perforations in the paper allowing the air to enter the tubes 430—433. The motion of the accordion pneumatic 406 is transmitted to the floating valve 516 in a manner similar to that just described and controls the amount of suction in the bellows 518.

When either the arm 509 or the corresponding arm on the other side is rotated, it will rotate the corresponding arm 561 thus rotating the shaft 559 in a counter-clockwise direction against the action of the spring 563. This will cause the valve 558 to gradually close the port 557. This valve acts as a spill valve so that when the suction in the bellows 514 and 518 is below a certain amount, this valve will be open, thus allowing air to enter the port 566, pass through

the chamber 565, port 558, chamber 556 and thence through the modulator pneumatic 417 to the pump 418. This relieves the pump of some of the unnecessary work which it 5 otherwise would have to do. Thus, when the suction in either of the bellows 514 or 10 518 is increased, the spill valve 558 will be closed thus automatically increasing the suction in the chamber 556.

When neither theme hole 437 nor 438 is open to the atmosphere the tubes 443 and 444 will be closed and therefore the chambers 582 and 583 in the theme primary valve box 408 will be exhausted through the bleed 15 holes 585 and 586 thus causing the pouches 580 and 581 and the corresponding valves 576 and 577 to be held in the positions shown in Figure 9^b. This will allow the tubes 542 and 543 to be connected to the atmosphere 20 through the chambers 570 and 571 and the ports 572 and 573. This will allow air to enter the valves 540 and 541, inflating them and thus causing discs 546 and 547 to close the ports 536 and 537. The suction in the 25 chamber 526 is the same as that in the bellows 514 as they are in constant communication through the duct 525. The suction in the chamber 526 controls the minimum suction in the chambers 532 and 533 by means 30 of the check valves 527 and 528. For, should the suction in either of these chambers be less than that in the chamber 526, the corresponding check valve will open, thus drawing the air from this chamber into 526 35 and reducing the pressure therein to that in the chamber 526. Under these conditions, the suction in the pipes 534 and 535 which supply the bass and treble pneumatics respectively, is controlled by the suction in 40 the bellows 514 which is known as the accompaniment regulator. Therefore, as long as no holes in the paper come opposite the holes 437 and 438 in the tracker bar, the intensity with which the notes of the instrument 45 are struck will be determined by the perforations in the paper which control the air entering the tubes 425—428.

If perforations in the paper strip come 50 opposite the holes 437 and 438 in the tracker bar, air will be admitted to the tubes 443 and 444, thus inflating the pouches 580 and 581 which lift the valves 576 and 577 thus connecting the two tubes 542 and 543 to the chamber 578 which is connected to the suction supply pipe 584. This causes suction to 55 be produced in the valves 540 and 541 thus collapsing them which opens the ports 536 and 537. This causes the chambers 532 and 533 to be put in communication with the 60 chambers 550 and 551 which are in communication with the interior of the bellows 518 known as the theme regulator, by means of the ducts 552 and 553. In this way, the suction in the pipes 534 and 535 which control 65 the suction in the bass and treble pneu-

matics 410 and 411 will be controlled by the theme regulator bellows 518. The suction in this in turn is controlled as previously described by the perforations in the paper strip which allows air to enter the tubes 430—433. 70

If only the hole 437 is exposed to the atmosphere, only the chamber 532 and therefore the bass pneumatics 410, will be connected to the theme regulator bellows 518, while the treble pneumatics 411, which are 75 controlled from the chamber 533, will be regulated by the accompaniment regulator bellows 514. In this way either all the pneumatics may be controlled by the bass or treble regulator perforations in the tracker bar or either half of these pneumatics may be controlled by either the bass or treble regulator, depending upon the proper cutting of the perforations in the paper which co-operate in the holes 437 and 438 in the 80 tracker bar.

The intensity of the suction in the pipe 534 is transmitted to the pneumatic 651 by means of the pipe 650, thus causing this pneumatic to take up a position dependent 90 upon the amount of this suction and tension of the spring 655 which may be regulated by the screw 656. The suction in the pneumatic 651 therefore determines the position of the arm 653 which by means of the primary 95 slide valve 662 controls the suction admitted to the bellows 668 and 669 thus controlling the position of the arm 673 in a manner similar to that previously described in connection with Figures 1 and 100 2. This causes the arm 676, link 677, rod 678, arm 679 and the reflectors 414 to assume a position dependent upon the suction in the pneumatic 651 and therefore the opening of the reflectors 414 is proportionate to the 105 strength of the suction in the bass pneumatics 410 and therefore to the intensity with which the bass notes are struck.

In a similar manner the reflectors 415 are controlled by the suction in the pneumatic 110 680 which is the same as the suction in the treble pneumatics 411 and therefore the reflectors 415 will be opened an amount proportional to the strength with which the treble notes are struck. 115

By manipulating the handles 449 and 457 air may be admitted to the tubes 443 and 444 thus controlling the primary valves 576 and 577 which in turn control the valves 540 and 541, thus connecting the bass or 120 treble pneumatics with the theme regulator when desired. These handles are used when paper rolls are being played which were not cut for automatic expression playing, but which are provided with four extra note 125 holes at each end of the scale which co-operate with the holes connecting with the groups of tubes 423 and 424. At this time the cut-out blocks 402 and 403 are in their 130 uppermost positions thus disconnecting the

tubes 425—428 and 430—433 and connecting up the groups of tubes 423 and 424 so that these will cause the corresponding pneumatics to function when the proper holes in the paper strip come opposite the corresponding holes in the tracker bar.

When it is desired to play the whole instrument softly, the handle 613 is moved from the "Concert" to the "Soft" position, thus uncovering the port 611 which allows air to enter the tube 610, thus inflating the pneumatic 606 which closes the port 607 thus shutting off the suction through this port, chamber 605, port 604, to the pipe 615 which is connected to the suction pump 418. When the port 607 is opened the suction normally passes from the pump 418 to the chamber 556, thus producing the full amount of suction in this chamber. When the port 607 is closed, however, the suction passes through the port 592 into the bellows 593, thence by the port 602 into the chamber 603. The bellows 593 will then be collapsed and the knife valve 594 will gradually close the port 602. As soon as this is closed, however, the spring 598 will tend to expand the bellows 593 thus gradually opening the port 602 again. In this way, the suction in the chamber 591 is regulated by means of the tension of the spring 598 so that the suction produced in the chamber 556 is only a fraction of that normally produced when the port 607 is open. In this way the entire dynamic action of the piano is reduced an amount depending upon the tension given the spring 598.

When a perforation in the paper strip comes opposite the hole 436 in the tracker bar, air will be admitted to the tube 442 and thence into the chamber 631 thus lifting the pouch 628 and the valve 635 which will connect the tube 644 to the suction chamber 627. This will cause the pneumatic 646 to be collapsed thus raising the rod 648 which operates the loud pedal action of the piano in a well known manner. In a similar manner when the hole 440 is exposed, air enters tubes 446, operating the valve 636, thus collapsing the pneumatic 647 in a manner similar to that just described. This will cause the rod 649 to be elevated which will operate the soft pedal action of the piano in a well known manner.

The suction in the chamber 627 is regulated by means of the bellows 622 which is controlled by the spring 624, thus when the suction in the bellows 624 and in the chamber 627 reaches a certain intensity the bellows will be collapsed and the knife valve 623 will gradually close the port 621, thus cutting off the suction supply. The bellows will then be opened under the action of the spring 624 again opening the port 621. In this manner the suction in the chamber

627 can be regulated by means of the tension of the spring 624. 65

The invention upon which this application is based is broader than the specific embodiment shown and described for the purpose of illustrating at least one of the ways 70 in which it may be employed. The scope of the invention is therefore to be understood as not being limited by the present specific description. I intend no limitations other than those imposed by the claims. 75

What is claimed is—

1. In a musical instrument, the combination with means for producing sound by percussion, of automatic means arranged in groups according to divisions of the musical 80 scale for operating the sound producing means to produce music, a plurality of modulating reflectors arranged in groups corresponding to the groups of operating means for variably controlling the sound waves 85 produced, and means controlled by said automatic mechanism operatively connected to said reflectors.

2. In a percussive musical instrument, a plurality of tuned vibratory elements, a plurality of striking mechanisms for vibrating said elements to produce sound, automatic playing mechanisms arranged in groups for operating the striking mechanism, an expression device for each group, a plurality of modulating reflecting devices arranged 95 in like groups for controlling the sound waves emitted from the instrument, and means interconnecting each of said expression devices and the respective group of reflecting devices for actuating said devices simultaneously with the expression device. 100

3. A modulating system for a percussive musical instrument comprising a plurality of modulating reflectors arranged in groups, 105 means for operating each group of reflectors independently of the remaining groups, automatic playing mechanism arranged in groups for operating the instrument to produce music, and means operatively interconnecting the groups of reflectors with the groups of playing mechanisms respectively. 110

4. A percussive musical instrument having a plurality of vibratory sound producing elements tuned to the different notes of the musical scale, a casing having controllable apertures for controlling the emission of sound from said elements, a group of modulating reflectors for variably closing the portion of said apertures proximate to 120 the vibratory elements tuned to the lower notes of the musical scale, a second group of modulating reflectors for variably closing the portion of said apertures proximate, to the vibratory elements tuned to the upper notes of the musical scale, automatic playing mechanism for actuating said vibratory elements, a modulating mechanism for 125

modifying the action of the portion of the automatic mechanism associated with elements tuned to the lower notes of the musical scale, an additional modulating mechanism for modifying the action of the portion of said automatic mechanism associated with the elements tuned to the upper notes of the musical scale, and means operatively inter-connecting said modulating mechanisms with said groups of modulating reflectors respectively.

5. In a musical instrument of the percussive type, the combination with a plurality of hammers, strings arranged to be set into vibration by the impact thereon of said hammers, manual means for actuating said hammers respectively, automatic means for actuating said hammers, a plurality of tone modulators arranged in groups according to 15 divisions of the musical scale for varying the intensity of sound emitted from different portions of the instrument respectively, means for each of said divisions of the musical scale for modifying the action of said automatic means to control the intensity of sound produced by the impact of the hammers, and means including a device controlled by each of said modifying means for actuating said tone modulators.

30 6. In a musical instrument of the percussive type, the combination with automatic means for playing the instrument arranged in groups, and a control device for controlling each group of said automatic means, of a plurality of tone modulators arranged in like groups for variably controlling the sound emitted from the instrument, and means actuated under control of said automatic means for controlling said modulators 35 respectively.

40 7. In a musical instrument of the percus-

sive type, the combination with a plurality of hammers, strings arranged to be set into vibration by the impact theron of said hammers, manual means for actuating said hammers respectively, a corresponding plurality of pneumatics for actuating said hammers arranged in a bass group and a treble group, a plurality of tone modulators arranged in like groups, for varying the intensity of sound emitted from different portions of the instrument, expression mechanism for each group of pneumatics for modifying the action of the respective pneumatics to control the intensity of sound produced by the impact of the hammers, and means including a device controlled by each of said expression mechanisms for actuating said tone modulators.

45 8. In a musical instrument, means for producing sound by percussion, automatic means for operating the sound producing means to produce music, a plurality of modulating reflectors for variably controlling the sound waves produced, and means controlled by said automatic mechanism for operating said reflectors.

50 9. In a reproducing piano, means for producing sound by percussion, automatic means for operating said sound producing means to produce music, automatic means for modulating the action of said operating means, a plurality of modulating reflectors for variably controlling the sound waves produced, and means controlled by said 55 automatic modulating means for operating said reflectors.

55 Signed at New York city in the county of New York and State of New York, this seventh day of October, A. D. 1925.

JOHN HAYS HAMMOND, Jr.
